UNITED STATES PATENT OFFICE.

FRANÇOIS LAGOUTTE, OF ASNIÈRES, FRANCE.

EXPLOSIVE-ENGINE.

SPECIFICATION forming part of Letters Patent No. 714,492, dated November 25, 1902.

Application filed June 26, 1900. Serial No. 21,680. (No model.)

To all whom it may concern:

Be it known that I, FRANÇOIS LAGOUTTE, engineer, a citizen of the French Republic, residing at Asnières, department of Seine, France, have invented certain new and useful Improvements in Internal-Combustion Motors, of which the following is a full, clear, and exact description.

This invention relates to certain improvements applicable to internal-combustion motors (gas, oil, and the like) for the purpose of increasing the cooling of the walls of the cylinders and the parts connected thereto.

These improvements consist of a means applicable to motors working with preëxhaust for insuring the cooling of the wall of the cylinder adjacent to the orifices of the preëxhaust, while also effecting a discharge of the burned gases into an exhaust-muffler.

20 The preferred form of my invention is illustrated in the accompanying two sheets of drawings, in which—

Figure 1 is a section of the motor, taken through the cylinder and exhaust-conduit. Fig. 2 is an enlarged sectional view of the automatic valve controlling the passage of the exhaust-gases through said conduit and the inlet of fresh air thereto, said valve being in a position permitting the inlet of fresh air to 25 the motor-cylinder. Fig. 3 is a similar section of said valve, showing it in a position for permitting the discharge of exhaust-gases through the conduit therefor and preventing the direct discharge thereof to the atmosphere.

30 I will describe the arrangement which enables me to cool the portion of the cylinder of a motor working with a preëxhaust adjacent to the said exhaust-ports. The preëxhaust is produced by forming in the wall of the cylinder a short distance from its forward end a number of openings which are uncovered during the period from the instant when the piston clears them to finish its forward 40 stroke until the moment when coming back it covers them again. During this time part of the burned gases will escape through the openings. When the piston performing its back stroke has passed these, the exhaust continues through the ordinary exhaust-valve. This method of working presents certain advantages, but it also entails certain inconven-

iences. The latter consist in that if the openings deliver to the outer air the exhaust gives rise to a loud noise, which is disagreeable, 55 and also if those openings deliver into a chamber communicating with a muffler the exhaust no longer takes place easily and the wall of the cylinder near the orifices becomes heated to an injurious extent.

60 The exhaust into the atmosphere but for the noise would be the most advantageous. In this case the working is as follows: When the piston performs its forward stroke (explosion) and has passed the openings, the 65 preëxhaust takes place until the return of the piston, and the wall near the holes is heated by reason of the passing of the hot gases. Then the piston in its backward stroke closes this outlet for the burned gases, and the remaining gases are exhausted through the exhaust-valve. The rearward stroke (compression) being finished, the piston again starts forward, performing the suction-stroke. The fresh gases enter into the cylinder and 70 when the piston uncovers the openings the fresh charge continues to be fed in through the inlet-valve; but at the same time air is admitted through the openings, cooling the surrounding wall, and this continues until 75 the moment when the piston, being at the end of its stroke, suction ceases. The piston coming back, a part of the air which enters into the cylinder is driven out through the openings, drawing with it a small quantity 80 of fresh gas with traces of burned gas, as well as a certain quantity of heat in consequence, until the moment when the openings are closed by the piston, which then compresses the fresh charge.

90 The result obtained with preëxhaust ports or openings delivering into the outer air is thus: first, partial exhaust through the sides of the cylinder, heating of the sides of the cylinder, and correspondingly diminished 95 temperature of the inner or closed end thereof; second, entry of cold air through the openings, and therefore cooling of the parts wherein the latter are formed; third, expulsion of a portion of the indrawn air, mixed 100 with traces of fresh and burned gases, some heat passing out therewith. In these conditions the wall of the cylinder adjacent to the preëxhaust-ports is cooled; but, as has been

seen above, this procedure is inadmissible by reason of the noise produced by the exhaust into the air. Exhaust into a chamber communicating with a muffler is indispensable; 5 but then the working becomes very defective. In such case the gases are not exhausted quickly enough by reason of the piping which conducts them to the muffler and by reason also of the back pressure in the latter 10 itself. At the time of the exhaust there takes place, when the piston uncovers the openings and continues its forward stroke, not a re-entrance of air, but a re-entrance of hot gases. The state of carburation of the fresh explosive 15 mixture which is at this moment in the cylinder is altered, the motor works badly, and the wall adjacent to the openings attains a high temperature, which is another cause of bad working.

20 I might avoid the re-entrance of the burned gases by causing the exhaust-ports to deliver into a chamber furnished with a valve which opens from the interior toward the exterior and would allow the gases to pass out and 25 prevent their returning; but then cooling of the wall around the openings would no longer take place.

My arrangement enables me to effect the escape into a chamber connected with a muffler, while retaining the advantages of the exhaust into the open air. It comprises an exhaust-chamber *b*, into which open the pre-exhaust-ports *a a*. This chamber is joined to a pipe *c*, conducting to the muffler, and 35 these together form a conduit for the passage of the exhaust-gases.

The communication of the chamber *b* with the pipe *c* is effected by means of a valve *d*, which through connected valve mechanism 40 permits at the desired time communication between the chamber *b*, and therefore the cylinder, and the outer atmosphere, as will be described.

The valve *d* is recalled to its seat by a 45 spring *r*, acting upon its rod *e*, suitably guided. This valve *d* is integral at its lower face with a sleeve *f*, open at its other end and which is fitted with openings *g*, of which the height is about equal to the extent of the 50 stroke of the valve *d*. This sleeve *f* serves also as a guide and slides within a suitable socket or bearing in the exhaust-chamber. In this socket, within which the sleeve *f* moves, are formed passages *h*, delivering from 55 the sleeve into the chamber *b*, as shown by the arrow.

The openings *g* of the sleeve *f* and the passages *h* are arranged in such a manner that when the valve *d* rests in its seat they coincide, and when the valve is raised from its seat they are no longer opposite one another. The interior space of the sleeve is in permanent communication with the exterior atmosphere by means of the orifices *k*, formed in 60 the wall of the fixed portion guiding the rod of the valve. The working of this arrangement is the following: At the moment when

the pre-exhaust takes place through the openings *a a* the burned gases entering into the chamber *b* raise the valve *d*, and the escape 70 takes place by means of a pipe *c*, conducting to the exhaust-muffler. At this moment the openings *g* of the sleeve *f* are not opposite the passages *h*. When the pre-exhaust ceases because the openings *a* have been again covered by the piston in its backward stroke, the valve *d* returns to its seat, and the openings *g* then coincide with the passages *h*, re-establishing communication between the escape-chamber *b* and the outer air. Consequently 80 when at the time of suction, which afterward takes place, the openings *a* will be again uncovered a re-entrance of fresh air will be produced in the cylinder through the openings *g* of the sleeve, the passages *h*, the chamber 85 *b*, and the openings *a a*. I thus obtain an efficient cooling of the wall of the cylinder in the neighborhood of the pre-exhaust-openings, while effecting this exhaust into a chamber 90 communicating with an exhaust-muffler.

I wish to remark that I do not limit myself to the arrangement of the sleeve *f* for setting up communication between the chamber *b* and the atmosphere. I may replace it by any one of numerous equivalent valve constructions well known to those skilled in the art 95 which would produce the same result.

The essential feature of my invention is the outwardly-opening check-valve *d* in the conduit provided for the exhaust-gases and air-inlet, such as *k*, to said conduit located at a point intermediate of the valve *d* and the ports *a*, through which the conduit for the exhaust-gases connects with the motor-cylinder, said air-inlet being controlled by valve 100 means which open when the valve *d* closes, and vice versa, or, to express the idea in other words, which open when there is induction of gases to the motor-cylinder and close when there is eduction of gases from said cylinder. 105

Having therefore described my invention, what I claim as new, and desire to protect by Letters Patent, is—

1. In an internal-combustion motor, the combination of a conduit for exhaust-gases 110 leading from the motor-cylinder, said conduit having an air-inlet near the point of connection to the motor-cylinder, valve means controlling the said inlet, valve means controlling the flow of gases through the conduit 115 and located farther from the motor-cylinder than the said air-inlet, and connecting mechanism which causes one valve to be open when the other is closed, and vice versa.

2. In an internal-combustion motor, the combination of a conduit for exhaust-gases 120 leading from the motor-cylinder, an outwardly-opening check-valve in said conduit, an air-inlet to said conduit between the check-valve and the connection to the motor-cylinder and a valve in said inlet which automatically opens upon induction of gases to said cylinder and closes upon the eduction of gases 125 therefrom.

3. In an internal-combustion motor, the combination of a cylinder having preëxhaust-ports located in the side walls thereof, a conduit for exhaust-gases connected thereto, an outwardly-opening check-valve in said conduit, an air-inlet to said conduit located between the connection to the cylinder and the above-described check-valve, and a valve which controls said air-inlet, said last-men-

tioned valve being arranged to open only when to the first-mentioned check-valve is closed.

In testimony that I claim the foregoing as my invention I have signed my name in presence of two subscribing witnesses.

FRANÇOIS LAGOUTTE.
